(57) **CLAIM**

The ornamental design for a tabletop point of purchase stand, as shown and described.

DESCRIPTION

FIG. 1 is a top plan view of a tabletop point of purchase stand showing my design according to a first embodiment; FIG. 2 is a bottom view thereof;

FIG. 3 is a front elevation view thereof;

FIG. 4 is a rear elevation view thereof;

FIG. 5 is a side elevation view thereof and the opposing side (not shown) is a mirror image;

FIG. 6 is a perspective view showing the tabletop point of purchase stand in-use;

FIG. 7 is a perspective view showing a cross-section of the tabletop point of purchase stand in-use taken across line 7-7 in FIG. 1;

FIG. 8 is a top plan view of a tabletop point of purchase stand showing my design according to a second embodiment;

FIG. 9 is a bottom view thereof;

FIG. 10 is a front elevation view thereof;

FIG. 11 is a rear elevation view thereof;

FIG. 12 is a side elevation view thereof and the opposing side (not shown) is a mirror image;

FIG. 13 is a perspective view showing the tabletop point of purchase stand in-use;

FIG. 14 is a perspective view showing a cross-section of the tabletop point of purchase stand in-use taken across line 14-14 in FIG. 8;

FIG. 15 is a top plan view of a tabletop point of purchase stand showing my design according to a third embodiment;

FIG. 16 is a bottom view thereof;

FIG. 17 is a front elevation view thereof;

FIG. 18 is a rear elevation view thereof;

FIG. 19 is a side elevation view thereof and the opposing side (not shown) is a mirror image;

FIG. 20 is a perspective view showing the tabletop point of purchase stand in-use; and,

(Continued)

FIG. 21 is a perspective view showing a cross-section of the tabletop point of purchase stand in-use taken across line 21-21 in FIG. 15.

The even-length broken lines are directed to environment, represent unclaimed subject matter, and form no part of the claimed design.

The tabletop point of purchase stand is shown with symbolic breaks in its length and width. The appearance of any portion of the article between the break lines forms no part of the claimed design. The long dash and short dash broken lines depict boundary lines that form no part of the claimed design.

1 Claim, 15 Drawing Sheets
